United States Patent Office.

GEOEGE M. HAY, OF AMERICUS, GEORGIA, ASSIGNOR TO HIMSELF AND HARVEY T. LITCHFIELD, OF BOSTON, MASSACHUSETTS.

Letters Patent No. 85,659, dated January 5, 1869.

IMPROVED MEDICAL COMPOUND.

The Schedule referred to in these Letters Patent and making part of the same.

To all whom it may concern:

Be it known that I, GEORGE M. Hay, of Americus, in the county of Sumter, and State of Georgia, have invented a new and improved Antidote for Drunkenness; and I do hereby declare the following to be a full, clear, and exact description of the same.

This invention consists in a combination of simple, common, and innocuous vegetable and animal substances, in the proportions described, whereby an effectual antidote to drunkenness is obtained, the use of which will not produce any injurious effects upon the system.

The compound which I employ for the purpose specified, consists of the several ingredients, and in the respective proportions, as herein set forth, to wit:

Calamus-root, one-half ounce; tincture gum-guacum, one and one-half ounce; beef-gall, or its equivalent, one-half pint; eel-skin, one-eighth ounce; cod-fish, one-eighth ounce; decoction of gourd, one-half pint; sweet milk, one-fourth pint; decoction of cherry-tree bark, one-fourth pint; decoction of poke-root, one-fourth pint; cows' urine, one-half pint.

These ingredients, having been thoroughly mixed, are added to one gallon of alcohol or pure spirits.

The medicine, thus compounded, is to be taken, before meals, three times a day; at first, in doses of two or three tablespoonfuls; afterwards, a single tablespoonful will suffice.

The eel-skin, codfish, and poke-root are not absolutely necessary to the medicine, but experience has proved that they increase its effectiveness, if used in the proportions set forth.

It is not necessary, of course, that the precise proportions of the several ingredients, as above given, should always be rigidly adhered to. They may be slightly varied, without sensibly affecting the general properties of the compound.

This medicine has been thoroughly tested in some of the most difficult cases of long-standing, habitual drunkenness that could be found anywhere in the country, and has resulted in an immediate and perfect cure, its effect being to destroy the appetite for intoxicating drinks, and to cause them to excite disgust and nausea whenever presented.

Having thus described my invention,

What I claim as new, and desire to secure by Letters Patent, is—

The compound above described, substantially as and for the purpose specified.

To the above specification of my improvement, I have set my hand, this 7th day of December, 1868.

GEO. M. HAY.
